UNITED STATES PATENT OFFICE.

EDWARD W. JENKINS, OF NORRISTOWN, PENNSYLVANIA.

MACHINE FOR TYING BUNDLES, &c.

1,339,396.

Specification of Letters Patent.

Patented May 11, 1920.

Application filed June 13, 1917. Serial No. 174,430.

To all whom it may concern:

Be it known that I, EDWARD W. JENKINS, a citizen of the United States, and resident of Norristown, county of Montgomery, and 5 State of Pennsylvania, have invented an Improvement in Machines for Tying Bundles, &c., of which the following is a specification.

The object of my invention is to provide a machine for conveniently, quickly and effectively tying or binding bundles, packages, boxes, etc., and especially adapted to commercial requirements of store and factory purposes where there are large numbers of bundles to be tied. My object is further to provide a suitable construction of bundle tying apparatus which shall be inexpensive and durable, and moreover, adapted to enable the bundle to be bound in a very tight and strong manner.

With these and other objects in view, the nature of which will be more fully understood from the description hereinafter, the invention consists in the novel construction of bundle tying apparatus as hereinafter 25 more fully described and defined in the claims.

Referring to the drawings:—Figure 1 is a front elevation of a bundle tying machine embodying my improvements; Fig. 2 is a 30 side elevation of the same; Fig. 3 is a plan view of the same; Fig. 4 is an inverted view of the knot-tying mechanism removed from the machine; and Fig. 5 is a sectional view on line $x-x$ of Fig. 2 showing a detail.

2 is a table upon which the bundle to be bound is placed, and is provided with downwardly extending feet or projecting portions 3 to support it above a counter or other suitable support 4 and to provide between 40 it and the table 2 a space or chamber 5 in which the knot-tying mechanism 6 is located. Extending upwardly from the table 2 is a bracket 7 carrying at its upper end a horizontal stud 8 upon which is journaled a binder arm 9 with provision for oscillation, and a fly wheel 10 having a crank arm 11 by 45 which it may be rotated.

The binder arm 9 is provided with a radial portion from the outer end of which extends a horizontal overhanging portion 12 terminating at its extreme end in a cord guide 13 in a vertical plane through the knot-tier 6, said cord guide being of tubular form and projecting obliquely to a radial line through the axis of the binder arm 55

(Fig. 2), so that when the binder arm is moved downwardly, the cord guide 13 will deliver the cord into the knot-tier 6, the cord passing through the slot 2^a in the table 2. 14 is a Y-shaped arm which is pivoted at 60 15 to the bracket 7, and one of the extensions of this arm is connected by a link 16 with a crank pin 17 on the fly wheel 10 so that when the fly wheel is rotated, the arm 14 is oscillated. The other extension of the 65 arm 14 is connected by a link 18 with the binder arm 9 at a short distance from its axis of oscillation. When the arm 14 oscillates, as above stated, it is manifest that through the link 18 the binder arm 9 is also 70 oscillated about the stud 8 from a vertical position, as shown in Figs. 1 and 2, through approximately 180 degrees to deliver the cord 19 into the knot-tying mechanism 6. In swinging about its axis, the radial portion 75 of the binder arm passes through the slot 2^b in the table 2, and the horizontal or overhanging portion 12 of the binder arm passes under the table so that its tubular guide end 13 may be brought into close operative position with the knot-tying mechanism 6. It will be observed therefore that the distance from the axis of the stud 8 to the edge 2^c of the table must be less than the radial clearance of the part 12 of the binder 80 arm from its axis of oscillation.

20 is a cord controlling arm for the cord and is loosely pivoted upon the stud 8 and provided at its outer end with a cord guide aperture 21 through which the cord passes 90 to a guide 22 on the binder arm 9. This cord controlling arm 20 is provided with a lug 23 which is free to oscillate between the stops 24 and 25 on the end of the bracket 7 (Figs. 1 and 2), so that the said arm 20 is 95 free to oscillate through approximately 90 degrees. 26 is a tension clamp under which the cord passes and by which tension is put upon the cord to prevent too much freedom in the passage of the cord to the binder arm. 100 This tension clamp consists of an arm at one end resting against the cord controlling arm 20, and having at the other end a clamping surface between which and the arm 20 the cord passes, the middle portion 105 of the tension clamp having an aperture 27 through which the cord 19 is guided into the tension device. The clamping tension is provided by a spring 28 pressing upon the tension clamp 26 and having its tension ad- 110

justed by means of a thumb screw 29 carried by the cord controlling arm 20. The construction of the cord controlling arm 20 and the binder arm 9 is such that when the binder arm returns to the position indicated in Fig. 2, it returns the cord controlling arm 20 also to the position indicated in Fig. 2. When the binder arm is oscillated in the forward position as in putting the cord 5 around the bundle and leading it into the knot-tying device 6, the cord pulls upon the cord controlling arm 20 and moves it forward with the binder arm until the lug 23 reaches the stop 25 when it is arrested, while the binder arm moves on to the knot-tying devices. This cord controlling arm 20 is therefore moved into the position shown in Fig. 2 by the binder arm 9 contacting with it on its return movement, and is also moved 10 in the other direction by the pull of the cord when the binder arm has been moved forward on its way to the knot-tier 6 and thereafter the cord necessary for wrapping the bundle and tying the knot is delivered under tension. By stopping the arm 20 and pulling the cord through the tension device by the binder arm, the cord necessary for wrapping about small as well as large bundles is assured. Ordinarily, the cord comes from 15 any suitable source of spool arranged overhead, passing downward through the aperture 27 in the tension clamp 26, thence upwardly between it and the arm 20, thence through the looped end 21 of the arm, thence 20 through the guide 22 of the binder arm 9, thence horizontally and through the tubular guide 13 at the free end of the binder arm, and thence downwardly through the slot 2^a to the cord clamp 31 (Fig. 4) of the knot-tying device.

While the knot-tying device may be constructed in any suitable manner, that shown is a type which has been developed by me and is excellently adapted for the purpose of my improved package binding machine. This knot-tying device consists essentially of a frame 32 which is pivoted upon a fixed stud 33 and adapted to be oscillated by a link 34, a lever 35, a second link 36 and a crank 37, the latter being secured to a vertical shaft 38 having a beveled pinion 39 at its upper end which is adapted to be engaged by a segmental rack 40 carried by and rotating with the fly wheel 10. This shaft 38 is journaled in a housing 41 extending downwardly from the fixed stud 8 upon which the fly wheel and the binder arm are journaled. The pinion 39 has a hub portion having a flattened surface 42 which, when in contact with the circular guide surface 43 of the hub of the fly wheel 10, holds the pinion and its shaft against rotation and with the crank arm 9 in the position indicated in Fig. 4. When the rack 40 is about 45 to engage the pinion 39, the termination of

the flat guiding surface 43 through the length of the arc of the rack 40, will permit the pinion to be rotated one revolution, so that it gives to the frame 32 of the knot-tying device one complete reciprocation. 70 Other mechanical devices may be employed for operating the knot-tier if so desired, but those described are found to be effective for the purpose.

Referring again more specifically to the knot-tying device, 44 is a looper bill which is journaled in the frame 32 and provided at its outer end with a pinion 45 which engages a rack 46 secured to the under side of the table 2. When the frame 32 is oscillated, 80 the looper bill 44 is caused to rotate, first in one direction and then in the other, and at the same time to travel in an arc about the stud 33 located to one side of the cord holder 31. The cord holder 31 may be of any suitable type, and is generally composed of a stationary member and a movable member by which latter the cord ends are frictionally held in the stationary member, and I do not restrict myself in any way to this particular detail of the knot-tying device. The general construction of the knot-tier herein illustrated is more fully described and illustrated in Letters Patent No. 1,239,793 and granted to me on September 11, 1917, and to 85 which reference is made for a more full description of a suitable knot-tier adapted to my particular improvements of this application.

In general, the operation of the apparatus 100 may be described as follows:—The parts being in the position indicated in Figs. 1 and 2, and the bundle or package to be bound being placed upon the table as indicated in dotted lines at A (Fig. 1), the fly wheel 10 105 is rotated by the handle 11, and this causes the binder arm 9 to be swung from its position shown to a position below the bundle and under the table to carry the cord into the knot-tier. While this operation is being 110 performed, the cord controlling arm 20 is moved forward with the binder arm until the stop 25 is reached before the completion of the downward movement of the binder arm, and thereafter the tension device of 115 the arm 20 supplies the cord under the requisite tension as the binder arm continues its advance to give cord to wrap the bundle and supply the knot-tying device so that the knot can be readily tied with proper 120 tension upon the cord. After the knot is tied, the continued rotation of the fly wheel causes the binder arm to be raised to its initial position, and in doing this, returns the cord controlling arm 20 again to the 125 position indicated in Figs. 1 and 2. During this operation and during a period of approximately one-quarter of a revolution of the fly-wheel, the knot-tier mechanism is put into operation for tying the knot, but during 130

the remaining portions of the revolution it is quiescent or inactive. At the completion of the operation of the knot-tying device, the cord is severed by a cutter 47, thereby liberating the bound bundle from the binder arm and knot-tier, and leaving the end of the cord from the binder arm in the cord holder of the knot-tier. When the bundle is removed, the parts will be in the position indicated in Figs. 1 and 2 and adapted to receive and bind another bundle or package. It will be observed that the cord controlling arm 20 is retained in its position shown in Fig. 2 by the binder arm and may rest against the stop 24 until pulled forward, and when the binder arm advances and wraps the cord about the bundle, this arm 20 will be drawn forward until arrested by the stop 25, it traversing approximately 90 degrees to give cord freely to insure the initial wrapping of the bundle. The final wrapping operation and tying of the knot is performed with the cord under tension.

While I have shown a crank handle 11 for rotating the fly wheel 10 and thereby imparting motion to the various parts, it will be readily understood that any suitable power may be applied to rotate the fly wheel if desired, and it will also be seen that the mechanism may be operated without requiring that the fly wheel shall completely rotate, as substantially the same results would be accomplished by making it oscillate through 180 degrees and which might be accomplished in any suitable manner. I therefore do not restrict myself to the particular means of applying the power for operating the machine, as this would be varied to suit the requirements or conditions available where the machines would be employed.

While I have in the present instance shown and described the preferred embodiment of my invention and which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a machine of the character stated, the combination of a table having a slit at one side about midway of its length, a knot-tier arranged under the table adjacent the blind end of the slit, a binder arm hinged on a horizontal axis above and to one end of the table and comprising a radial arm having a lateral overhanging portion arranged lengthwise of the table and having its free end formed with a cord guide, the length of the radial arm being sufficient to carry the lateral portion beyond the slotted side of

the table whereby it may pass under the same and close to the knot-tier, and means to rock the binder arm and operate the knot-tier alternately.

2. In a machine of the character stated, 70 the combination of a table having a slit at one side about midway of its length, a knot-tier arranged under the table adjacent the blind end of the slit, a binder arm hinged on a horizontal axis above and to one end of 75 the table and comprising a radial arm having a lateral overhanging portion arranged lengthwise of the table and having its free end formed with a cord guide, the length of the radial arm being sufficient to carry the 80 lateral portion beyond the slotted side of the table whereby it may pass under the same and close to the knot-tier, cord controlling means pivoted axially with the hinged binder arm for freely supplying cord 85 to the knot-tier during the tying of the knot, and means to rock the binder arm and operate the knot-tier alternately and also to oscillate the cord controlling means toward the binder arm when the latter is completing its forward movement to the knot-tier.

3. In a machine of the character stated, 90 the combination of a table having a slit at one side about midway of its length, a knot-tier arranged under the table adjacent the 95 blind end of the slit, a binder arm hinged on a horizontal axis above and to one end of the table and comprising a radial arm having a lateral overhanging portion arranged lengthwise of the table and having its free 100 end formed with a cord guide, the length of the radial arm being sufficient to carry the lateral portion beyond the slotted side of the table whereby it may pass under the same and close to the knot-tier, means to 105 rock the binder arm and operate the knot-tier alternately, and a cord controlling lever pivoted adjacent to the axis of the binder arm for guiding the cord to the binder arm, stops to limit the oscillation of the cord 110 controlling lever, means in association with the binder arm and its operating means for oscillating the cord controlling lever alternately in opposite directions.

4. In a machine of the character stated, 115 the combination of a table having a slit at one side about midway of its length, a knot-tier arranged under the table adjacent the blind end of the slit, a binder arm hinged on a horizontal axis above and to one end 120 of the table and comprising a radial arm having a lateral overhanging portion arranged lengthwise of the table and having its free end formed with a cord guide, the length of the radial arm being sufficient to 125 carry the lateral portion beyond the slotted side of the table whereby it may pass under the same and close to the knot-tier, means to rock the binder arm and operate the knot-tier alternately, and a cord controlling le- 130

ver pivoted adjacent to the axis of the 5 binder arm for guiding the cord to the binder arm, an adjustable tension device on the lever for regulating the tension on the cord controlled thereby, stops to limit the oscillation of the cord controlling lever, means in association with the binder arm and its operating means for oscillating the cord controlling lever and its associated 10 tension device alternately in opposite directions.

5. In a machine of the character stated, the combination of a table having legs to hold it elevated and at one side provided 15 with a cord slot midway of its length and on the same side near one end having a wide slot substantially parallel to the cord slot, a binder arm of angular form having a radial portion hinged to oscillate in a plane 20 through the last mentioned slot in the table and having an overhanging part transverse to the slots and terminating in cord guide in substantial alinement with the cord slot, the length of the radial portion being 25 greater than the distance from the axis of oscillation to the slotted side of the table whereby the overhanging portion may pass over said side and under the table, a knot-tying means 30 under the table adjacent to the blind end of the cord slot, and means for operating the binder arm and knot-tier alternately.

6. In a machine of the character stated, the combination of a table having legs to 35 hold it elevated and at one side provided with a cord slot midway of its length and on the same side near one end having a wide slot substantially parallel to the cord slot, a binder arm of angular form having a radial 40 portion hinged to oscillate in a plane through the last mentioned slot in the table and having an overhanging part transverse to the slots and terminating in cord guide in substantial alinement with the cord slot, the 45 length of the radial portion being greater than the distance from the axis of oscillation to the slotted side of the table whereby the overhanging portion may pass over said side and under the table, a knot-tying means 50 under the table adjacent to the blind end of the cord slot, and means for operating the binder arm and knot-tier alternately comprising hand operated reciprocating devices for oscillating the binder arm and connected 55 intermittently rotating means for operating the knot-tier.

7. In a machine of the character stated, the combination of a table having legs to hold it elevated and at one side provided

with a cord slot midway of its length and 60 on the same side near one end having a wide slot substantially parallel to the cord slot, a binder arm of angular form having a radial portion hinged to oscillate in a plane 65 through the last mentioned slot in the table and having an overhanging part transverse to the slots and terminating in cord guide in substantial alinement with the cord slot, the length of the radial portion being greater 70 than the distance from the axis of oscillation to the slotted side of the table whereby the overhanging portion may pass over said side and under the table, a knot-tying means 75 under the table adjacent to the blind end of the cord slot, and means for operating the binder arm and knot-tier alternately consisting of a rotary member having a crank pin and a rack segment, a pivoted frame having a linked connection with the binder arm and with the crank pin, a pinion adapted to be 80 intermittently rotated by the rack segment, a crank shaft rotated by the pinion and jointed connections between the crank shaft and the knot-tier means.

8. In a machine of the character stated, the combination of a table having an opening therein through which the binding cord may reach from the knot tier to the bundle upon the table and also having means extending below the same to hold it suspended 90 and to provide means for its support so as to leave a space below it, combined with a frame arranged in fixed relation to the table and laterally to one side thereof, a rock shaft supported in said frame and having 95 secured thereto a binder arm so shaped as to have its cord binding end extended above the table and radially at a considerable distance from the rock shaft, the radial distance from the axis of oscillation of the rock 100 shaft to the cord binding end of the binder arm being greater than the distance between said axial line of the rock shaft and the table, whereby the end of the binder arm may be swung to a position below the table, 105 a knot-tier arranged below the table and at a distance above the bottom of the support therefor, whereby the said knot-tier has a fixed relation to the table and shielded thereby, and means to rock the rock shaft 110 and the binder arm alternately with the operation of the knot-tier.

In testimony of which invention, I hereunto set my hand.

EDWARD W. JENKINS.
